UNITED STATES PATENT OFFICE.

PLATO G. EMERY, OF CHICAGO, ILLINOIS, ASSIGNOR TO THE ADAMS & WESTLAKE COMPANY, OF ILLINOIS.

WINDOW OR CURTAIN FIXTURE.

SPECIFICATION forming part of Letters Patent No. 624,775, dated May 9, 1899.

Application filed November 5, 1898. Serial No. 695,606. (No model.)

To all whom it may concern:

Be it known that I, PLATO G. EMERY, of Chicago, in the county of Cook and State of Illinois, have invented certain new and useful Improvements in Window or Curtain Fixtures, of which the following is a specification, reference being had to the accompanying drawings and to the letters of reference marked thereon.

10 My invention relates more particularly to such window or curtain fixtures as are intended for use in railway-cars and are of that class in which the curtain may be raised or lowered to any height within the limit of the 15 frame, with its cross-bar always horizontal with the top and base of the frame, and remain at any height to which it may be moved.

A curtain-fixture of the class to which my invention is more especially adaptable is 20 shown in United States Patent No. 513,307, granted January 23, 1894, to George A. Criss-son. After each trip the car or cars are usually sent to the yard and cleaned, the curtains being pulled out to their full length and 25 dusted, and heretofore in the use of the said patented device it has been necessary for the cleaner to get in behind the curtain. It is impracticable or difficult to do this, inasmuch as the cross bar or rod carried by the curtain 30 cannot be readily removed from its frame or guides, and heretofore the only way the car-cleaner could get at the back of the curtain was to pull it down to its lowest limit and then grasp it at the middle and pull it out- 35 wardly. Aside from the danger of tearing the material of which the curtain is made such an operation is an awkward one; and the present invention has for one of its objects to enable the curtain to be more readily 40 cleaned than heretofore. Other objects are to permit of the bodily removal of the curtain and fixture from the framing without detaching the cables from the cross bar or rod or leaving them dangling from their upper 45 fastenings, to allow of the repair of the curtain when necessary, and to facilitate generally the use of curtains and fixtures of this class.

Efforts have been made to effect the easy 50 manipulation of the curtain by causing its

bottom to be readily attachable to and detachable from the cross-bar or curtain-stick without removing the latter from its frame or guides; but prior to my invention, so far as I am informed, no means have been devised whereby a cord attached to diagonally opposite corners of the frame may be readily detached from one or more of said corners and as readily reattached, thus permitting the curtain to be easily handled, and while I here 55 show certain preferred mechanical constructions under which my invention may be put into effect I do not limit myself thereto, but intend to cover, broadly, means whereby such cord may be expeditiously detached from 60 such corner or corners and as readily reattached in order that the entire curtain-fixture 65 may be removed or the curtain manipulated for cleaning or repair.

In the accompanying drawings, Figure 1 is 70 a face view or elevation of a railway-car window provided with a curtain-fixture constructed according to my invention and in position, the frame or casing of the window being partly shown in section. Fig. 2 is 75 a view showing the curtain-stick removed from its frame or guides. Fig. 3 shows the invention applied to an open or summer car. Fig. 4 is an enlarged perspective view of the catch, the figure showing also at the right 80 in perspective a portion of the cord, wire, or chain with the ball attached, all as hereinafter described. Fig. 5 is a vertical longitudinal section of the same catch, showing in full lines the ball caught thereby. Fig. 6 85 is a vertical longitudinal section of the catch, showing the ball in the act of being expelled therefrom and the mode of effecting its expulsion. Fig. 7 is a sectional view showing a modification in the form of the ball. Fig. 90 8 is a similar view showing a further modification thereof.

Similar letters of reference indicate similar parts in the respective figures.

Referring to Fig. 1, A is the window-frame, 95 and B the curtain, which may be made of any suitable design or construction. The curtain B is of fiber, leather, or other suitable material and is here shown as wound upon a spring-roller D, the function of which is to tend at 100

all times to wind the curtain up on the roller, and thus raise the curtain to its highest position. As here represented my invention is applied to that class of curtains or fixtures described in said Patent No. 513,307, in which the curtain is provided with a tube carried at its bottom and two cords connected to diagonally opposite corners of the window-frame and passing through the said tube, each cord crossing the other. The tube is what is here termed the "cross bar or rod."

As here indicated, the lower end of the curtain B is provided with a tube C, which may be made of metal or other preferred material, at each end of which a suitable guide-piece D' is placed, the ends of the guides being in contact with the cords, wires, or chains D², as explained in the said Crisson patent, No. 513,307. In the present adaptation of my invention to a window or curtain fixture of the description set forth in the said patent I do not limit myself to any particular arrangement of guide-pieces, construction of tube or bar, or other details, all of which may be variously modified by the skilled mechanic.

E is a catch, Figs. 4, 5, and 6, one of which is attached, preferably, to each lower corner of the frame A, although, if desired, the upper corners may be furnished with similar catches. The part e of the catch E has an upper bifurcated hook e' and is screwed to the frame A, as shown, being provided with side wings e², in which is pivoted a lever e³, its upper arm being curved, as seen at e⁴. The curved part of the upper arm of the lever e³ is normally forced against the part e by means of a spring e⁵.

The lower end of each cord D² (or in one form of my invention seen enlarged in Figs. 7 and 8 each end of each cord) is furnished with a ball, which as an entirety is represented by F, each ball when in position being caught under the bifurcated hook e' and against the curve e⁴ of the upper arm of the lever e³, the cord D² passing within and through the slot of the bifurcated hook e'.

As shown in Fig. 7, the ball is made in three pieces—viz., the perforated stud f, the perforated ring f', and the nut f². The cord D², passing through the perforated stud f and its slightly-projecting ring f', is clamped by turning the nut f². When it is desired to change the tension of the cord, this can readily be done by loosening the nut, slipping the stud and ring upon the cord, and again tightening up the nut.

As shown in Fig. 8, the ball is made of two parts only—viz., the perforated stud f and the nut f². The cord D², passing through the perforated stud, is clamped between the head of the stud and the nut f², and when it is desired to change the tension of the cord so clamped this may be done by loosening the nut, slipping the stud upon the cord, and tightening the nut, as will be readily understood.

The ball F, of either construction, is so

shaped as to fit snugly under the bifurcated hook e' of the catch and against the curve e⁴ of the upper arm of the lever e³. 70

In front of each catch and screwed or otherwise attached to the inner part of the frame is a plate, shield, or escutcheon G, having a perforation g opposite the lower arm of the lever e³. When the cord D² is to be detached 75 from the catch E, this may be done by pressing the lower arm of the lever inward by means of a small instrument g or an ordinary nail passed through the hole g' in the plate G, which will cause the curve e⁴ of the upper arm 80 of the lever e³ to push the ball out of contact with the hook e' of the catch and the attached cord out of the slot in the hook, both ball and cord being forced through the groove or guide in the frame, when the tension upon the cord 85 will at once and automatically cause the ball to fly up from the hook e', thus disengaging the cord from the frame. (See Fig. 6.)

The upper end of each of the cords may be attached to an ordinary clip or fastener H, or, 90 if preferred, a catch such as has been described may be placed at each upper corner of the frame for maintaining contact between the cord and the frame. By using four catches it will be seen that the entire curtain and fixture may be readily and almost instantly removed from the frame without detaching the cords or cables from the tube or cross-bar C, so that the whole may be lifted out from the frame for any purpose. This arrangement is 95 a great convenience and obviates the necessity which would otherwise exist of leaving the cords, wires, chains, or cables dangling from the top clips.

This device is to a certain extent automatic 105 in its action, because of the tension which always exists to a greater or lesser degree in the cord. This tension upon the release of a ball from its catch will cause the instantaneous and automatic starting of that end of the 110 cord from its catch, preventing the necessity of removing the cord therefrom by manual action.

Fig. 3 shows the adaptation of the invention to an open or summer car, this being one 115 of the most important uses for which it is designed. It will be understood that the application is the same as to a closed car, the standards of the frame of the open car being the equivalent of the window-frame of the closed 120 one.

The construction of what I term the "ball" at the end of the cord, whether that of Fig. 7 or of Fig. 8, provides for the convenient taking up of the slack of the cord or adjusting 125 its tension by unscrewing or untightening the sections of the ball, when they can be moved on the cord and retightened or re-clamped and again sprung into the holders. (See Fig. 4.)

The plate, shield, or escutcheon G prevents unauthorized access to the catch, and while the detachment of the cord can be readily accomplished by the use of a suitable tool it 130

is believed that sufficient security is afforded to prevent tampering with the fixture.

While I have here shown what is considered to be a simple, efficient, and easily-operated device, I do not confine myself to this particular construction, as it is evident that modifications thereof having the same functions may be devised by a skilful mechanic without the exercise of invention.

10 By the use of the word "curtain" herein I wish to also include a flexible screen, a slatted blind, a spring-actuated window-sash, or other equivalent device.

It is also to be understood that this invention is applicable to other adaptations of cords for preserving the parallelism of the bottom edge of a curtain or its equivalent.

Having thus described my invention, what I claim is—

20 1. In a cord holding and detaching mechanism, a cord, and a device adjustably secured to the cord, combined with a catch for engaging the said device and holding the cord under tension, and having means adapted to 25 be manually operated for detaching said device from the catch, substantially as set forth.

2. In a cord holding and detaching mechanism, a cord, and a device adapted to slide thereon and be clamped thereto, combined 30 with a catch for engaging the device and holding the cord under tension, and having means capable of being manually operated for detaching said device from the catch, substantially as set forth.

30

3. In a cord holding and detaching mechanism, a cord, and a device adapted to slide thereon and be clamped thereto, combined with a catch for engaging the device and holding the cord under tension, and having a lever capable of being manually operated for 40 detaching the device from the catch, substantially as set forth.

4. In a cord holding and detaching device, a cord and a ball adapted to slide thereon and be clamped thereto, combined with a catch 45 for engaging the ball, a lever mounted in the catch and adapted to be manually operated for detaching the ball from the catch, and a spring for automatically returning the lever to normal position, substantially as set forth. 50

5. In a tension device for a cord, the combination of a holder, a lever pivoted thereto, a stud, the cord passing through a perforation therein, and a nut for clamping the stud on the cord, substantially as set forth. 55

6. A clamping device consisting of a cord, a stud adapted to slide on the cord, a clamping-nut on the stud, a perforated ring also on the stud, through which the cord passes, and a fixed holder for engaging the stud after it 60 has been clamped to the cord, substantially as set forth.

In testimony whereof I hereunto set my hand and seal.

PLATO G. EMERY. [L. S.]
